UNITED STATES PATENT OFFICE.

MARGARET A. YORK, OF NEW YORK, N. Y.

DESIGN FOR A CHILD'S COSTUMER.

Application filed July 14, 1927. Serial No. 22,752. Term of patent 7 years.

To all whom it may concern:

Be it known that I, MARGARET A. YORK, a citizen of the United States, and a resident of the city of New York, borough of Manhattan, in the county and State of New York, have invented a new, original, and ornamental Design for a Child's Costumer, of which the following is a specification, reference being had to the accompanying drawing, forming part thereof.

Fig. 1 is a view in side elevation of a child's costumer showing my new design.

Fig. 2 is an edge view thereof.

I claim:

The ornamental design for a child's costumer substantially as shown.

MARGARET A. YORK.
